UNITED STATES PATENT OFFICE

EMIL WEINHEIM, OF NEW YORK, N. Y.

METHOD OF COATING AND IMPREGNATING WEBS OF FLEXIBLE MATERIAL

Application filed June 17, 1929, Serial No. 371,389, and in Germany July 13, 1925.

My invention relates to a method of coating and impregnating webs of flexible material, for instance fabric, paper or other fibrous goods.

5 It has already been proposed to impregnate single layers of fabric or the like by means of distributing and squeezing rollers. It is an object of my invention to provide a stronger and more durable article of the 10 kind described. To this end I combine a plurality of layers, each of which has been treated as described, into a single web.

I may also supply a water-proofing or other compound to the layers immediately 15 before combining them.

In the drawings affixed to this specification and forming part thereof a machine embodying my invention is illustrated diagrammatically by way of example in elevation.

20 The machine illustrated is designed to combine two separate layers into a single web, but it is understood that I am not limited to the combination of two layers but may combine any number of layers, as required.

25 Referring now to the drawings, the machine here illustrated comprises two identical units, each having a supply reel 1 and 1', respectively, from which the layers 2 and 2' which are to be combined, are taken to a common reel 3 after having been finished. As the units are identical, only the unit at the right will be described in detail, the corresponding parts of the other unit being 30 marked with the same reference numerals, 35 but indexed.

The supply reel 1 is provided with two rollers 4 and 5 which are actuated by suitable means, not shown, and feed not the reel 1 but the layer on the reel so that variations in the velocity due to the varying diameter of the supply on the reel are eliminated as would be the case if the reel 1 were rotated at constant velocity. The velocity at 40 which the rollers 4 and 5 feed the material is obviously a function of their circumferential velocity and is not influenced by the diameter of the reel. Obviously, means, not shown, must be provided for varying the radial distance of the rollers 4, 5 from the axis 45 of the reel 1 as the diameter of the supply

varies. 6 is a stationary roller at some distance from the reel 1, and 7 is a movable squeezing roller, the layer 2 passing between the two rollers. Rotation is imparted to the roller 6 by any suitable means, not shown, 55 while the roller 7 is rotating idly. Any suitable means may be provided for exerting pressure on the idle roller 7 which means in the present instance is illustrated as a toggle lever system comprising a lever 8 which is fulcrumed at 9 in the frame of the machine, a lever 10 at the end of which the roller 7 is rotatably carried, and a weight 11 which is suspended by a chain 12 from the pivot 13 of the system. The pin about which 60 the roller 7 rotates is moving on a track 14. In this manner horizontal thrust is exerted on the roller 7 which forces it toward the roller 6 so that the layer 2 is compressed between the two rollers. The compound which 65 is applied to the layer is stored in a tank 15 and is discharged or extruded through a pipe 16 at some point intermediate the reel 1 and the idle roller 7. The compound is distributed uniformly and forced into the fibres of the 70 layer 2 by means of the roller 7. The weight of the roller 7 does not influence the layer as it is absorbed by the track 14 so that only the horizontal component of the vertical pressure exerted by the weight 11 is exerted on 75 the layer. The web now passes on toward a pair of feed rollers 17 and 18 which are also rotated by suitable means, not shown. As will appear the two layers 2 and 2' are combined into a single web 19 between these 80 rollers and this finished web is wound on the reel 3. A scraper 20 may be provided intermediate the roller 6 and the roller 17 for removing any excess of compound and for assisting in its uniform distribution. It is understood that any means other than the scraper 85 might be provided.

Above the point where the two layers are combined into the web 19 a tank 21 is provided from which an additional compound, such as a water- and weather-proofing liquid, may be applied to the space between the two layers 2, 2'.

The goods obtained by my process may be waterproof and reinforced leather substi- 100

tutes, oil cloth, rubber cloth, paper and other fibrous materials, and may be used, for instance, as waterproof covers for vehicles. It will be understood that I obtain not less than 5 two layers of fabric or the like, each coated or impregnated separately, and a layer of a waterproofing compound between each two layers. As mentioned, any number of layers of fabric or the like may be provided 10 alternately with layers of weatherproof emulsions, liquids and the like, or mixtures of such materials, so that each layer increases the strength of the material until the combined cloth or the like is practically secured 15 against destruction and its several layers cannot be separated. In combining two or more fabrics or the like into a single compound web as described, each fabric is subjected to the same treatment so that the several fabrics 20 to be combined are of exactly uniform size and quality and the web obtained by combining them is of uniform size, quality, thickness, width and specific gravity throughout.

I wish it to be understood that I do not 25 desire to be limited to the exact details of operation and construction shown and described, for obvious modifications will occur to a person skilled in the art.

In the claims affixed to this specification 30 no selection of any particular modification of the invention is intended to the exclusion of other modifications thereof and the right to subsequently make claim to any modifications not covered by these claims is express- 35 ly reserved.

I claim:

1. The method of making webs from several layers comprising treating each layer separately with a compound, combining the 40 several layers into a single web, and applying a compound between said layers.

2. In a machine for making webs from several layers, the combination, with a unit for treating each layer separately, of means 45 for combining the layers into a single web, and of means for applying between said layers a compound at the point where they are combined.

3. The method of coating or impregnating 50 a web of flexible material, comprising applying plastic material to a layer, applying plastic material to another layer, causing said two layers to move relatively toward each 55 other, causing them to travel in close parallel relation, applying waterproofing material to said layers at the point where they start for the said parallel movement, applying pressure to said layers while they are moving in parallel, and keeping the tension 60 and traveling velocity of the webs equal and uniform throughout all these operations.

In testimony whereof I affix my signature.

EMIL WEINHEIM.
